Neil O. Preston

UNITED STATES PATENT OFFICE.

CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK.

POINT DETECTOR.

Application filed November 1, 1920. Serial No. 421,009.

To all whom it may concern:

Be it known that I, CHARLES S. BUSHNELL, citizen of the United States, residing at Rochester, in the county of Monroe and State of New York, have invented certain new and useful Improvements in Point Detectors, of which the following is a specification.

This invention relates to circuit controlling devices, commonly called point detectors, which are used in connection with switches in interlocking systems for railroads for the purpose of safe-guarding the movement of trains over such switches. The point detector is associated with the switch machine, or switch and lock-movement, operating the switch-points, and is directly connected to said switch points, so that the operation of the point detector is dependent upon the position of the switch points and the locking and unlocking operation of the switch machine. The point detector governs directly or indirectly the circuits of the signals governing traffic over this switch, and acts to signal trains to stop if the switch points are not in their proper position or are not properly locked.

It is desirable that such a point detector, like all devices used in railway signaling systems, should be guarded as far as possible against dangerous failure from any cause. In one type of switch machine and point detector, to which the present invention is more particularly applicable, the normal or reverse positions of the point detector (corresponding to the normal and reverse position of the switch point) are not selected by the switch machine but are dependent solely upon the connections between the point detector and the switch points. With such an arrangement it may happen that the point detector will falsely assume one position, although the switch points are in the opposite position, in case all the connections to the switch points are broken, or accidentally disconnected.

The primary object of the present invention is to obviate the possibility of a false failure as outlined above; and in a specific embodiment of the invention this is accomplished by making the operation of the point detector dependent upon the movement of the lock rod of the switch machine. Other objects of the invention will appear hereinafter as the characteristic features of

the construction, functions and mode of operation of my improved point detector are described in detail.

In describing the invention I will refer to the accompanying drawings, in which— 60

Figure 1 is a diagrammatic view, partly in perspective and with some parts broken away or spread apart for clearness, which shows the principal operating parts of a switch machine of well known construction 65 having my improved point detector applied thereto;

Fig. 2 is a plan view of the point detector, with some parts broken away;

Fig. 3 is a vertical transverse section 70 through the point detector on the line 3—3 in Fig. 2;

Fig. 4 is a similar transverse section on the line 4—4 in Fig. 2; and

Fig. 5 is a diagrammatic view illustrating the more significant parts of the point detector, together with its connection to the points of a single slip switch, these parts being selected and arranged to facilitate explanation of the construction and operation 80 of the point detector. 75

I have illustrated my improved point detector in connection with a switch machine similar to that shown and described, for example, in the patent to W. K. Howe, No. 85 1,288,595, dated December 24, 1918; but it should be understood that the invention may be used in connection with the other specific constructions of switch machines, by making appropriate changes in mechanical 90 details.

Referring to Fig. 1, the stock rails of a conventional switch are designated 1, and the movable switch points 2. These switch points 2 are connected to a throw bar T and a lock rod LR of the switch machine, these parts being shown separated and to different scales for convenience and clearness. The switch machine is operated by an electric motor M of any suitable type, which is 100 shown as a series wound direct current motor having an armature 3 and a field 4. The armature shaft of the motor M drives a main gear 5 journaled by a fixed stud 6 through suitable reduction gearing. This reduction 105 gearing, as shown, comprises a bevel pinion 7 meshing with a bevel gear 8 which drives a shaft 9 through a friction clutch 10 (shown enclosed); a pinion 11 on said shaft 9 meshing with a gear 12 on a second shaft 110

13; and a pinion 14 on said second shaft meshing with the main gear 5. The main gear 5 is rotated in one direction or the other to reverse the switch points by changing the direction of rotation of the motor armature.

Fastened eccentrically to the main gear 5 is a downwardly extending driving pin 15 which carries two freely revoluble rollers 16 and 17 at its lower end. This driving pin 15 is moved by the main gear 5 in a circular path indicated by the dot and dash line 18. The upper roller 16 cooperates with the edges of a laterally opening jaw or cam 19 in the throw rod T, and acts to reciprocate said throw bar as the main gear 5 is rotated first in one direction and then in the other. Extending lengthwise of the switch machine is a locking plunger LP which is guided at one end by a block 20 and at other points 20 in its length by suitable lugs (not shown). This locking plunger LP is provided with an enlarged head 21 in which is formed a cam slot 22 of a general elliptical shape, the lower roller 17 being disposed to cooperate 25 with the edges of this cam slot and reciprocate said locking plunger as the main gear 5 is rotated. The locking plunger LP carries a lock dog 23 arranged to engage behind shoulders 24-24¹ on the throw bar T; 30 and another lock dog 25 fastened to said locking plunger is arranged to enter normal and reverse notches (not shown) in the lock rod LR, thereby holding the throw bar and the lock rod against movement and locking 35 the switch points. In the present invention, the lock dog 25 is formed with a longitudinal groove with flared or beveled ends, as best shown in Fig. 5, so as to cooperate with the point detector as hereinafter explained.

40 The lock rod LR is shown as made up of two bars, which in practice are made relatively adjustable by suitable means (not shown) for the purpose explained in the prior patent above mentioned.

45 The circuit controller for governing the operation of the switch machine comprises in general two units or groups of contacts and their operating means, designated as a whole O and P, one for controlling the operating and indication circuits (hereinafter termed the operating circuit controller), and the other for controlling the circuits of the pole changer coils (hereinafter termed the pole changer coil controller). Each unit 50 comprises a plurality of fixed contact springs or fingers, as 26, arranged in rows along opposite sides of the machine and carried by suitable fixed bars 27 of insulating material. Two separately movable blocks or contact carriers 28 and 29 are arranged to be shifted back and forth from one side of the machine to the other. Each of these contact carriers has a panel of insulating material, 55 and 31, respectively, to which are fastened contact strips, as 32, adapted to bridge pairs

of the contact springs 26. The contact carrier 28 of the operating circuit controller O is supported by the cores 33 of the normal and reverse pole changer coils 34 and 35, and is shifted back and forth by an arm 36 70 loosely mounted on a vertical shaft 37 and having a jaw straddling a pin 38 connected to said contact carrier. Thus, contact carrier 28 may be shifted electrically by the pole changer coils 34 and 35, or mechanically 75 by a contact shifter designated as a whole CS. The contact block 29 of the pole changer coil controller P is operatively connected to the contact shifter CS by a pin 39 and a jaw 40 integral with said contact 80 shifter.

The contact shifter CS is an irregular shaped piece, comprising a bottom plate 41, carrying normal and reverse operating rollers 42-42¹, and a centering roller 43; a top 85 portion 44; and two upright side bars 45-45¹. The centering roller 43 cooperates with two parallel guide strips 46 fastened to the locking plunger LP and having their ends beveled in such a way that when the locking plunger is moved to its unlocked position (to the right as shown) these guide strips 46 cooperate with the roller 43 and move contact shifter CS to the middle position and hold it there until the locking 90 plunger is returned to its locked position. The contact shifter CS is shifted to its extreme positions by normal and reverse selecting plungers 47-47¹ which are carried in brackets 48-48¹ fastened to opposite 100 bars of the lock rod LR. These selecting plungers 47-47¹ are arranged to be projected by the lock dog 25 against the roller 42 or 42¹ as the switch machine locks up. When the contact shifter CS is moved to its 105 middle position, the contact carrier 29 is likewise moved to its middle position, but on account of the space between arm 36 and each of the side bars 45, contact carrier 28 is not moved. When the contact shifter 110 CS is operated to its extreme position, however, both of the contact carriers 28 and 29 are shifted to the corresponding extreme position.

Briefly reviewing the operation of the 115 switch machine, which is explained at length in the prior patent above mentioned, when current is applied to the operating motor M, the main gear 5 is turned by said motor through the reduction gearing in one direction, (clockwise according to the position of the parts in Fig. 1); and as the driving pin 15 is moved in its circular path 18, the lower roller 17 engages one edge of the cam slot 22 and shifts the locking plunger LP 120 (to the right as shown) to its unlocked position, thereby unlocking the throw bar T and the lock rod LR. The guide strips 46 put the contact shifter CS to the middle position. This in turn places the contact car- 125

rier 29 in its middle position, bridging both sets of contact fingers 26 associated therewith, so that the circuit through either the normal or reverse pole-changer coils 34 or 35 may be set up, thereby enabling the machine to be reversed in mid-stroke if desired, in a manner characteristic of this system and fully explained in the prior patent above mentioned. As the driving pin continues its movement, the upper roller 16 engages the jaw 19 of the throw bar T and shifts said throw bar to the other extreme position. The lower roller 17 now engages the other edge of the cam slot 22 and returns the locking plunger LP to its locked position. During the movement of the switch points, the lock rod LR is shifted from the position shown to the other position, on account of the movement of the switch points, and this places the selecting plunger 47¹ opposite the roller 42¹, so that when the lock dog 25 returns to the position shown in Fig. 1, it carries with it said selecting plunger 47¹ and causes the contact shifter CS to be swung to its other extreme position. This movement shifts the operating circuit controller O, thereby breaking the motor operating circuit and setting up the indication circuit. The motor M now acts as a generator, in the manner characteristic of this dynamic indication system, and the generated current is transmitted to the tower through the indication magnet of the lever corresponding to the switch in question, with the result that this lever is released and the operator is thus informed that the desired movement of the switch has been accomplished. The operation of unlocking and moving the switch points back to their former position is similar to that described.

In connection with this type of switch machine it will be noted that the locking plunger LP is moved out (to the right) and then back to the same position during the cycle of operation of moving the switch points from one position to the other. This kind of locking, conveniently called "out and in" locking, does not allow the position of the point detector to be selected by the locking plunger, so that my improved point detector is particularly applicable to switch machines having this type of locking.

It will also be noted that the lock rod LR constitutes an essential element in the cycle of operation. If this lock rod LR is removed from the machine, the contact shifter is not operated from its middle position; and if the connection between this lock rod and the switch points is broken, the contact shifter CS will not be properly shifted to the other position, but will merely be returned to its former position, with the result that current is not cut off from the operating motor nor the correct indication circuit established. In short, the presence

and proper operation of that lock rod LR is essential to the proper performance of the switch machine, and its absence or failure to move will be immediately detected.

Referring now to the construction of my improved point detector, I have shown my invention in connection with a specific type of point detector which comprises a plurality of detecting bars D, which are connected in any suitable way, as shown, for example in Fig. 5, to each point, or to each pair of points, of a switch, or movable point frog, as the case may be. These bars D extend transversely of the switch machine, and are guided at the sides thereof by the frame or casing of said machine.

The operating parts of the point detector are disposed above the detecting bars D and are supported from a suitable frame work or casing. The circuit controlling element of the point detector, which I have termed a contact cradle C, comprises two side members 50, which are disposed vertically, and are connected at their tops by a horizontal flat bar 51, and at the bottom by an operating lug or foot 52, having one end beveled, as best shown in Fig. 5. To the top bar 51 is fastened a block 53 of suitable insulating material which has embedded therewith a number of metallic contact pieces 54. A plurality of resilient contact fingers 55 are fastened at their ends to blocks 56 of suitable insulating material which extend parallel with the top bar 51 and are suitably fastened, as by screws, to the frame work or casing of the device. When the contact cradle C is in one extreme position, as shown in Fig. 4, its contact pieces 54 electrically connect the several pairs of contact fingers 55 on that side; when said cradle is swung to a neutral or middle position, the contact fingers on both sides are disconnected; and when said cradle is swung to the other extreme position, the several fingers 55 on that side are electrically connected. In this way suitable controlling circuits may be selectively made and broken in accordance with the position of the switch points, and these circuits may be used to control directly, or indirectly, the signals governing traffic over the switch in question.

The contact cradle C is supported by a rocker yoke Y so as to be able to rock on a horizontal axis about a point near its middle, and also move bodily up and down to a limited extent. This rocker yoke Y comprises two side arms 57 connected at their middle by a transverse web 58. These side arms 57 carry at one end a horizontal pin 59 which passes through the side members 50 of the contact cradle C and constitutes its rocking support, said pin 59 being held in place by small transverse pins or the like. The side arms 57 are pivotally supported at their upper ends by a pin 60 which is supported in downwardly extending lugs of

4 a horizontal top plate 61. Between the web 58 of the yoke Y and the top plate 61, is disposed a compression coiled spring 62, said spring being held in place by appropriate 5 bosses as shown in Fig. 3. In the side members 50 of the contact cradle C are fastened two roller supporting shafts 63, these shafts extending horizontally lengthwise of said cradle and on opposite sides of its supporting pin 59. On these shafts 63 are loosely journaled two sets or groups of rollers N and R.

To one side member 50 of the contact cradle C is fastened an inverted U-shaped yoke 65, the ends of which overlie the projecting ends of the brackets 48-48¹ on the lock rod LR, so that with the lock rod in one position, as shown in Fig. 4, one of said brackets 48 is under one end of the yoke 65.

20 The detecting bars D pass under the rollers N and R and above the foot 52 of the contact cradle C, as shown in Fig. 4; and these bars are provided with narrow grooves or notches 66 in their upper faces, which 25 have rounded ends and are slightly wider than the rollers. The length and arrangement of the notches 66 is slightly different according to the use to which the point detector is put, and one arrangement suitable 30 for a single slip switch is illustrated in Fig. 5.

The operation of the point detector can be more readily understood from consideration of its simplest application to a single 35 slip switch which has been shown diagrammatically in Fig. 5. Two detecting bars D¹ and D² are used, these bars being connected by rods 67 and 68, respectively, to the switch lugs of the two switch points 2. The detecting bar D¹ is provided with a short notch 66^a which comes underneath one of the rollers of the normal set N, when the switch points are in the normal position as shown. This bar D¹ also has a longer notch 66^b arranged to come underneath a roller in the 40 reverse set R, when the switch points are moved to the reverse position. The detecting bar D² is similarly provided with a short notch 66^a and a long notch 66^b arranged to receive rollers of the reverse and 45 normal sets in the corresponding positions of the switch points. It will be noted that a short notch 66^a in one detecting bar is opposite the long notch 66^b in the other detecting bar. This arrangement of long and 50 short notches is provided so that the two detecting bars may be applied to switches having different movements or throws, without 55 changing the notching.

60 With the switch points in the normal position and locked, as shown in Fig. 5, the normal notches 66^a and 66^b of the bars D¹ and D² are under the normal rollers N. Since the locking plunger LP is in the 65 locked position, the lock dog 25 is clear of the

foot 52 of the contact cradle C. The spring 62 tends to move the pin 59, and consequently the contact cradle C as a whole downward; and as a result said cradle rocks to the normal or left hand position as 70 shown, fulcruming about the point where the reverse rollers R bear upon the upper edges of the detecting bars.

When the switch machine is operated the flared ends of the groove in the lock dog 75 25 engage the foot 52 of the contact cradle C and force it to its middle position by a wedging or cam action. The contact cradle is maintained in this middle or neutral position with all circuits broken, so long as the 80 switch machine is unlocked.

As the switch points are thrown, the lock rod LR is shifted thereby (to the left as shown) from its normal position to its reverse position, and the extension on the 85 bracket 48¹ is shifted to come under the opposite end of the yoke 65, so that the contact cradle may swing from the middle position to its reverse position (to the right as shown) but cannot swing back to its normal 90 position. The detecting bars D¹ and D² also move with the switch points, so that the reverse notches therein come under the reverse set of rollers R. When the locking 95 plunger has been moved to its locked position, contact cradle C is then free to assume its reverse position, on account of the action of the spring, in the same way as previously explained.

From the foregoing it can be seen that the 100 movements of the contact cradle C are dependent upon the locking plunger LP, the position of the detecting bars acting collectively, and finally upon the position of the lock rod. When the switch machine is unlocked, the contact cradle is held in its middle or neutral position by the lock dog 25. If the detecting bars D¹ and D² do not both 105 move, then their notches do not line up and allow the rollers to drop in. Further, the cooperation of the yoke 65 with the brackets 48-48¹ prevents the contact cradle C assuming a position out of correspondence 110 with the position of the lock rod. In this way the operation of the parts are coordinated in such a way as to check each other. 115

To illustrate the important feature of the 120 present invention, assume that the connections between all of the detecting bars, as D¹ and D², are broken, or that the maintainer or other person has disconnected these bars for some reason and neglected to re-connect them. If this happens, the detecting 125 bars will not move, and the contact cradle C would be free to assume its former position, except for the fact that the lock rod LR has been shifted and one of the brackets 48 or 48¹ engages the yoke 65 and prevents such movement of the contact cradle. The yoke 65 does not touch the brackets 48-48¹ ex- 130

cept when something happens to prevent movement of all of the detecting bars. In short, the yoke 65 together with the brackets 48-48¹, constitutes a safety check upon the position of the contact cradle C. In this connection it should be understood that the dangerous condition obviated by the yoke 65 will exist only in case all of the detecting bars fail to move. If only one bar fails to move, then the contact cradle C is held in its middle position, since the notches for neither set of rollers are all lined up. It should also be remembered that the lock rod LR cannot be removed from the machine, or fail to move when the switch points are thrown, without immediate detection at the next operation of the switch machine. My improved point detector, therefore is fully protected against any false failure.

20 My improved point detector, like others of this type, detects abnormal or improper movement of either one of a pair of switch points, since all the detecting bars must be in a corresponding position to allow the 25 rollers to drop into the notches. If one of the switch points is displaced while the switch machine is not operating, the bar connected to that point will force up the roller in its notch and shift the contact cradle C to its neutral position. When such 30 roller is in a short notch, the contact cradle C is put in its neutral position by very slight movement of the corresponding detecting bar; and the arrangement of notches in rollers is such that, when the switch point to 35 which a given detecting bar is connected becomes the closed point of the switch, then the short notch of this detecting bar is under one of the sets of rollers. The open 40 point of a switch may move to a considerable extent in practice without causing appreciable danger to train movement, and consequently a long notch which facilitates 45 the adjustment of the device for switches of different throws, affords all the desired protection. The short notches in the detecting bars may of course, be used for both the open and closed switch points; but it is preferred to use an arrangement of short 50 and long notches to provide the requisite adjustment for variation in the throw of the points of different switches, or even the same switch.

55 The particular construction illustrated has a capacity of four detecting bars, as shown in Fig. 2; and this provides for the detecting of all four points separately of a double slip switch or a movable point frog. When the detection of only two switch 60 points, or of four switch points in pairs, is desired, either two detecting bars alone may be employed, or four detecting bars coupled together in pairs. Also the detecting bars may be connected with the switch machine on either side of the switch. These,

and other adaptations and modifications of the structure of the point detector, are disclosed and claimed in the application of R. C. Leake, 283,369, filed March 18, 1919, the present invention being in the nature of an improvement in the type of point detector disclosed in said Leake application.

70 I have shown and described one specific embodiment of my invention and in the form I have devised for use with a point detector and a switch machine of one particular construction, but I desire to have it understood that the construction and arrangement of parts illustrated is susceptible of various changes and modifications 75 in practice without departing from the invention.

80 What I claim as new and desire to secure by Letters Patent of the United States, is:—

1. In operating mechanism for switch points of the type which comprises a lock rod and a point detector comprising detecting bars, said lock rod and detecting bars being connected to the switch points, a circuit controlling element movable from a neutral position to either of two extreme positions and having its extreme position selected in accordance with the position of the detecting bars acting collectively, and engageable members on said circuit controlling element and said lock rod cooperating to prevent a movement of said circuit controlling element to an extreme position unless the lock rod is in a corresponding position.

85 2. A point detector for switch machines having a lock rod and a locking plunger for locking said lock rod, comprising a plurality of detecting bars, and circuit controlling means governed by the detecting bars 90 and the locking plunger and also having its position dependent upon the position of the lock rod.

95 3. A point detector for switch machines having lock rods connected to switch points, comprising a plurality of detecting bars, a three-position circuit controller governed by said bars, and engageable members on said circuit controller and the lock rod for preventing movement of said circuit controller out of correspondence with the position of said lock rod.

100 4. In a device for governing switch points, a horizontally movable lock rod coupled to the switch points, a plurality of detecting bars also connected to said switch points, a three-position circuit controlling element mounted to rock about a horizontal axis, and cooperating means on the lock rod and said element to prevent movement of said element to one extreme position or the other unless the lock rod 105 is in a corresponding position.

110 5. A point detector of the type in which a plurality of detecting bars govern the op-

eration of a circuit controlling element, the combination with said element, of other means connected to the switch points for determining the position of said element.

6. A point detector for electrically operated switch machines of the type in which the operating or indication circuits for the machine are controlled by a lock rod connected to the switch points, and in which 10 said lock rod is held in its extreme positions by a locking plunger, comprising a circuit controlling element movable from a middle position to either of two extreme positions, means for forcing said element to 15 its middle position independently of other control thereof while said locking plunger is in its unlocking position, cooperating means associated with said lock rod and said element preventing movement of said element to an extreme position unless the lock 20 rod is in a corresponding position, and a plurality of detecting bars separately connected to the switch points and acting to shift said element to an extreme position 25 subject to the control thereof by said lock rod and locking plunger only if all of said detecting bars are in a corresponding extreme position.

7. In operating mechanisms for switch 30 points, the combination with a lock rod connected to the switch points, a plurality of independently movable detecting bars separately connected to the switch points, and circuit controlling means having its 35 operation dependent upon the position of the detecting bars acting collectively and also upon the position of the lock rod.

8. In a point detector for switch machines having a lock rod connected to the 40 switch points, a plurality of independently movable detecting bars separately connected to the switch points, a rocking contact carrier governed by said bars, and cooperating means on said carrier and said lock rod for determining the extreme positions 45 of said carrier.

9. In a point detector for switch machines having a lock rod, a three-position circuit controlling element mounted to rock 50 on a horizontal axis, contacts selectively opened or closed in the respective three different positions of said element, and cooperating means associated with said element and the lock rod to prevent movement of the element to either extreme position unless the lock rod is in the corresponding extreme position.

10. In a device of the character described, 55 the combination with a lock rod made up of two relatively adjustable bars, a rocking circuit controlling element, means connected to the switch points for rocking said element to its extreme positions in correspondence with the position of the switch points, and cooperating means associated

with said element and with said bars for independently determining the extreme position of said element in accordance with the position of the lock rod.

11. A point detector for switch machines 70 provided with a lock rod and a locking plunger, a plurality of independently movable detecting bars, and circuit controlling means governed jointly by said lock rod, locking plunger, and said detecting bars 75 acting collectively.

12. A point detector for switch machines provided with a lock rod and a locking plunger, a three-position circuit controlling element, a plurality of independently movable detecting bars, means for forcing said circuit controlling element into its neutral position by the movement of the locking plunger to its unlocked position, cooperating means associated with the lock rod and said circuit controlling element to prevent said element assuming either extreme position unless the lock rod is in a corresponding position, and means operatively connecting the circuit controlling element and said detecting bars for permitting said element to assume either extreme position if all of said bars are in a corresponding position, the movement of any one of said bars from an extreme position acting to force said element 90 to its neutral position.

13. A point detector for switch machines provided with a lock rod connected to the switch points, a circuit controlling element movable from a central position to either of two extreme positions, a plurality of independently movable detecting bars separately connected to the switch points, said circuit controlling element assuming one or the other extreme positions provided all of the detecting bars are in a corresponding position and being forced to its neutral position if any one of said bars is displaced from its corresponding extreme position, and cooperating engageable members on said element and the lock rod for preventing movement of the element to either extreme position unless the lock rod is in a corresponding position.

14. A point detector comprising a rocking contact carrier, a U-shaped yoke secured to said carrier, a lock rod, and means on the lock rod cooperating with said yoke to prevent said carrier assuming an extreme position unless the lock rod is in the corresponding position.

15. In a device of the character described, the combination with a lock rod and a plurality of independently movable detecting bars, said lock rod and detecting bars being separately and individually connected to the switch points, a locking plunger for locking the lock rod in its extreme positions, and a rocking circuit controller having its position determined by said lock 130

rod, locking plunger and detecting bars acting separately and individually.

16. A point detector for switch machines having a reciprocable locking plunger for locking the switch points in both positions, a plurality of detecting bars connected to the switch points, circuit controlling means governed by said detecting bars and actuated to a neutral position by the unlocking movement of said plunger, and other means connected to the switch points for independently determining the position of said circuit controlling means.

17. In a device of the character described, the combination with a three-position contact element, a lock rod, a locking plunger and a plurality of detecting bars, said lock rod, locking plunger and detecting bars acting separately and independently to determine the position of said contact element.

18. A point detector of the type described comprising, a spring pressed rocking circuit controlling element, a lock rod, connected to the switch points, and engageable members on the lock rod and said element for preventing movement of the element to either extreme position unless the lock rod is in a corresponding position.

19. In a combined point detector and switch operating mechanism, a lock rod, a plurality of detecting bars, a locking plunger movable transversely to said lock rod and detecting bars, and circuit controlling means adjacent the point of intersection of said plunger, lock rod and detecting bars and separately actuated thereby.

In testimony whereof I have affixed my signature.

CHARLES S. BUSHNELL.
